TOY SNOW TRAIN

Patrick E. E. Coderre, Port Chester, N. Y.

Application March 7, 1940, Serial No. 322,788

4 Claims. (Cl. 46—216)

This invention relates to toy trains, and more particularly to electrically operated toy trains designed to simulate the construction and operation of a train traveling over snow-covered tracks.

A principal object of the invention is to provide an electrically operated toy train including a sectional third-rail track, as used for electrically operated trains, a snow-train mounted on the track and including therein a snow plow car, a locomotive and tender, a combination baggage and "flanger" or scraper car, and a caboose car, all releasably coupled together, the engine simulating a steam engine and having devices and means for simulating the puffing and emission of smoke, the ringing of a bell, the blowing of a whistle, fire in the fire-box, head and tail lights, and the like, as well as a simulation of snow on the track, the whole constituting as near as practicable consistent with simplicity, durability and cheapness, a replica in toy form of a modern "snow-train."

Other objects and advantages will appear from the following specification, reference being had to the accompanying drawings which exemplify certain preferred embodiments and structural features of my invention, and wherein:

Fig. 1 is a fragmentary top plan view of two sections of track joined together.

Fig. 2 is a longitudinal section on the line 2—2 of Fig. 1.

Fig. 3 is a detail of center or third rail connection.

Fig. 4 is a sectional detail of one of the outside rail connections.

Fig. 5 is a cross section on the line 5—5 of Fig. 1.

Fig. 6 is a side elevation of the toy snow train as outlined, the same being mounted on its track.

Fig. 7 is a longitudinal horizontal section, on the scale of Fig. 6, through the snow plow car.

Fig. 8 is a longitudinal vertical section, on an enlarged scale, through the locomotive and tender.

Fig. 9 is a side elevation, on an enlarged scale, of the whistle mechanism in its preferred form.

Fig. 10 is a side elevation of the whistle producing mechanism on the same scale as Fig. 9. The whistle being shown in section.

Fig. 11 is an enlarged detail of the smoke producing assembly in its preferred form.

Fig. 12 is a cross section of the puff producing element on a greatly enlarged scale.

Fig. 13 is a detail of the double cam, for operating the bell and puff element in the assembly represented in Figure 18.

Fig. 14 is a detail of the car couplers.

Fig. 15 is a schematic view of the bell ringing device in a preferred form.

Fig. 16 is a top plan view of the flanger or snow-scraping car; a center section being broken out thereof.

Fig. 17 is a top plan view of a snow plow in a modified form.

Fig. 18 is a vertical section through a locomotive of a modified form.

Fig. 19 is a cross section on the line 19—19 of Fig. 18.

Fig. 20 is an enlarged detail of the whistle bellows operating mechanism in a modified form.

Fig. 21 is a detail of a reed unit for siren.

In constructing the invention I provide a miniature track-bed 5 composed of oblong sections 6 of papier-mâché or other suitably cheap and non-conductive material, the same being

preferably arched in cross-section and centrally depressed to form raised marginal bosses or ribs 6a spaced apart and extended in parallelism, and a central trough 7. The sections 6 are preferably of equal dimensions, and formed to fit nicely

together end to end to complete the track-bed 5. For a circular or oval track-bed (not shown), all or certain of the sections would of course be cut somewhat angularly at their ends, or all or certain of the sections would be somewhat curved,

so that the assembled sections would assume the desired and conventional formation of an endless circular or oval track-bed. The sections are all finished or painted on their upper sides to represent the cross-ties 8 and ballast of sand and

gravel 9 of an actual track-bed. Rails 10 of thin metal strips slightly greater length than the sections and curved in plan where necessary to follow the curvature or bends of the track-bed, are mounted in parallelism along the bosses 6a and

are anchored in place by striking down teeth 11 medially from the rails, piercing the teeth down through the bosses and then up-setting them underneath, as shown. Electrical continuity

through all the rails at each side is provided by positioning the rails at one end flush with the ends of their sections, turning down the excess rail length at their opposite ends as shown at 12 and then anchoring spring metal clips 13 at

one end 14 to the under sides of the rail ends falling flush with their section ends and extending the free ends 15 of the clips down under and across the down-turned ends 12 of the rails of the contiguous sections. The "third" rails 16 are formed by doubling thin metal strips length-

wise upon themselves and striking out teeth 17

which are pierced down centrally along the troughs 7 of the sections 6 and then upset, as with the outer rails. The rails 16 are also cut to the approximate length of their respective sections 6 upon which they are mounted. These rails are releasably linked together, and the sections 6 likewise held together, by forming a head 18 on one end of the rails and a C-shaped yoke 19 on the slightly extended ends of the contiguous rails, the heads removably fitting down into the yokes as the track sections are laid. Thus the track-bed and rails are constructed and assembled.

For the train to run on the described track-way, I provide a snow-plow car 20 of oblong formation and box-like structure, including top 21, bottom 22, sides 23 and ends 24. This car is carried on low, flanged wheels 25 affixed at the ends of axles 26 journaled at 27 below the bottom of the car at each end, the wheels being spaced to fit and run upon the track rails 10. Doors 28 are hinged at 29 to the forward margins of door-openings 30 formed in the opposite sides of the car. The hinges 29 are formed and set at their knuckles 31 to move stiffly, so as to maintain the doors in either open or closed position, as they may be placed or turned. The sides 23 and doors 28 extend well down and close to the rails 10 when mounted thereon, to facilitate the operation of the car as a "snow-plow."

A small shaft 32 is journaled at 33 axially through the car 20, its rear extended end carrying a spear-headed coupling 34, square in cross-section at its base, and a miniature rotary "snow-plow" 35 being mounted at the forward extended end. A stationary plow 36 is supported forwardly of the rotary plow, at the ends of braces 37 extended at the sides of the car. Thus the plow 35 may rotate rearwardly of the fixed plow 36.

A toy locomotive 40 and tender 41 follows the car 20 upon the track-way, this unit being oblong, and conforming generally to the car 20. The locomotive simulates a real steam engine and tender, including hollow boiler 42, cab 43, smoke-stack 44, bell 45, whistle 46, electric head-light 47, "cow-catcher" 48, fire-box 49, and "cat-walk" 50, while an electric tail light 51 is set in the rear end of the tender 41.

The locomotive and tender are carried upon flanged wheels similarly to the car 20. The wheels 52, 53, 54 of the locomotive are affixed at the ends of axles 55 journaled at 56 through the pendent sides 57 of the locomotive, forwardly, centrally and rearwardly. The wheels are gaged to fit the tracks, and the two forward axles carry longitudinally aligned spur gears 58 centrally and rigidly mounted thereon, while the rear axle is formed with a looped crank 59.

The bell 45 is swingingly supported on a crank-shaft 60 journaled through a loop 61 affixed atop the boiler, rearwardly of the stack 44, and a cord 62 secured at one end to the crank 59, thence passed up over a pulley 63 supported in a bracket 64 extended from the cab 43, and thence extended forwardly through the open front of the cab and secured at its forward end to the crank of the bell shaft 60, provides means for automatically ringing the bell as the locomotive moves on its track.

The hollow, box-like tender 41 comprises a bottom 65 of insulation material, top 66, sides 67 and ends 68, and similarly to the locomotive it is borne upon two pairs of flanged metal wheels 69 affixed to metal axles 70 journaled at 71 below the bottom of the tender, at front and rear.

A small motor 72 is mounted medially within the tender 41 upon the insulation bottom 65 thereof, and is electrically connected at its intake side through a lead 73 with a spring metal trolley loop 74 secured at 75 centrally and longitudinally under the bottom 65 and motor 72. Small metallic trolley wheels 76 are mounted on metallic stub shafts 77 journaled at 78 in the forked ends of the loop 74, these wheels being grooved on their peripheries and thereby operatively seated on the third-rail track 16 and adapted to travel thereon for picking up current for the motor. The other side of the motor is grounded to the metal frame. The motor 72 is positioned with its shaft 79 extended centrally and longitudinally of the tender, locomotive and snow-plow car, and is connected at 81 with a shaft 82 journaled at 83 through rear and front ends of the locomotive. The extended forward end of the shaft 82 at the front of the locomotive has anchored thereon in axial alignment a squared tubular coupling 84 into which the spear-head coupling 34 of the car 20 slides, as the two are moved together. This form of shaft coupling enables rotary movement of the shaft 82 to be transmitted to the shaft 32 and to the rotary plow 35.

A worm 85 is keyed on the shaft 82 within the locomotive 40, immediately over and intermediate of the two gears 58, and is placed in mesh with a worm-gear 86 carried on a shaft 87 journaled in the sides 57. The gear 86 is aligned and in mesh with the two gears 58. Rotation of the shaft 82 by the motor 72 now rotates the wheels 52 and 53 in the same direction, and causes the locomotive and attached cars to move over the track-way.

The whistle 46 is tubular and is firmly seated down through the top of the locomotive to the right of the shaft 82. This whistle is operated by a reciprocating plunger 89 having its stem depended vertically into the body of the locomotive. A rack 90 is rigidly affixed at its upper end to the plunger stem and depends in alignment therewith, the lower end of the rack passing slidably through a slot 91 in the bottom of the locomotive and spaced to the right of the shaft 82, whereby the rack is held in vertical, operative alignment with the whistle.

A segmentally toothed wheel 92 is keyed on the shaft 82 with its teeth 92a in operative alignment with and formed and dimensioned to mesh with the formations of the rack 90. Coiled tension springs 93 secured at their ends to the top of the locomotive and upper end of the rack 90, normally draw the rack and plunger upwardly, and this action, suddenly done, serves to blow the whistle through the air suddenly compressed and forced therethrough. This sudden movement of the rack and plunger is accomplished by the stripped side 92b of the wheel 92. The spacing of the rack 90 laterally to the right of the shaft 82 and the diameter of the wheel 92 is such that as the wheel rotates the teeth 92a will engage the rack 90 and draw the plunger 89 downward against the springs 93, but as the stripped side 92b turns to the rack this engagement will cease, and the springs will jerk the plunger up into the whistle tube, thus sounding same. The assembly as shown in Figure 7 contemplates the operation of the whistle described, on the forward movement of the locomotive. To operate a whistle on the backward movement, a duplicate whistle assembly (not here shown) would be installed at the left side of the shaft 82. In each case the upward move-

ment of the rack is limited to hold same in position for engagement with the teeth 92a on the downward movement thereof.

A small bellows 95 is supported horizontally in the hollow body of the locomotive by a bracket 96 secured at its ends to the top of the locomotive and to the upper side of the bellows. A peripherally grooved disk or wheel 97 is keyed eccentrically to the shaft 82 below the bellows 95, and a ring 98 is seated in the groove thereof for peripheral sliding movement. A stem 99 is rigidly anchored at its lower end to the ring 98 and at its upper end is hingedly connected to the lower side of the bellows 95. The upper side of the bellows is apertured at 100 and a small pipe or tube 101 is seated at its lower end as shown at 102 over this aperture, the upper end being inserted and seated as shown at 103 in the lower end of the smoke stack 44. An air intake valve 104 is seated through the lower side of the bellows. Now as the shaft 82 rotates the bellows 95 is worked in and out by the eccentric disk 97, drawing in air through the valve 104 and expelling it through the stack 44. A flat, circular, hollow puff-producing baffle element 105, having offset ports or apertures 106-107 through its sides is seated in the lower end of the stack 44, and as air is forced therethrough, the puffing of the air simulates that of an actual locomotive.

A small insulated electric resistance or heating coil 108 is mounted in the stack 44 above the baffle 105, and a screen cap 109 is removably mounted at the top of the stack. Smoke producing material of any kind, such as punk (not shown) may be inserted in the stack on the coil 108, and the resulting smoke will be emitted in puffs, also in simulation of a steam locomotive. The headlight 47 is in the form of a small electric bulb seated in an insulated socket 47a, seated through the front end of the locomotive. The fire box 49 is apertured at its sides, as shown at 49a, and a red electric bulb 110 is seated inside in an insulated socket 110a, to simulate fire of a locomotive. The tail-light 51 of the tender is in the form of a small electric bulb, seated in its insulated socket 51a through the rear end of the tender 41.

A flanger or snow-scraper car 111 follows the tender 41 upon the track-way, the same being of oblong formation and box-like structure, including top 112, bottom 113, sides 114 and ends 115. This car also is carried on low flanged wheels 116 affixed at the ends of axles 117 journaled at 118 below the bottom of the car at each end, the wheels being spaced to run on the rails 10. Doors 119 are hinged at 120 to the forward margins of the door openings 121 formed in the opposite sides of the car. The sides 114 of this car, as well as the bottoms of the doors 119, fall close to the rails 10, similarly to the arrangement of the locomotive and tender and the snow-plow car. Arcuate slots 122 are formed through the car sides rearwardly of the doors 119, and a pair of flat "snow" scrapers 123 are adjustably mounted in these slots. The scrapers are formed arcuately on their lower margins 124 to conform to the convexity of the margins of the track-bed 5. The scrapers have flat, narrow shanks 125 passed freely through the slots 122 and bent forwardly inside the car, where they are pivotally secured by small bolts 126 passed through the shanks and the sides of the car. The bolts 126 are tightened to hold the shanks 125 frictionally against the sides of the car and so that they will maintain themselves in any adjusted position, 75

whether raised from or moved close to the track-bed 5. A cross-bar 127 is rigidly connected at its ends to the extremities of the shanks 125, whereby the scrapers are made to move in unison.

5 A caboose 128 of oblong box-like structure similar to the car 111, and similarly carried on wheels 129 fitted to the tracks, may be added to complete the train. This caboose may be either of conventional design as here shown, or it may have doors mounted thereon, similar to the doors 28 of the car 20.

10 The cars are releasably coupled together by means of flat spring tabs 130, 131 anchored to and extended medially in alignment from the adjacent ends of the cars, one tab 130 having an inwardly beveled latch 132 depended from its outer end, and the other tab 131 being formed with a relatively large eye 133 and down turned extremity 134, whereby as the cars and locomotive are pushed together, they will automatically couple together by the latches 132 moving over the down-turned extremities 134 and falling into the eyes 133. To uncouple, the extremities 134 are pulled downward to release the latches 132.

15 The several electrical elements described, such as head light 47, tail-light 51, heating coil 108, fire-box bulb 110, are all electrically connected and energized in a conventional manner, as by a wire (not shown) connecting said elements in series with the motor intake and ground connections. Likewise the third rail is to be electrically energized in the conventional manner, and is not here shown.

20 Any desired form of "make-believe" or mock-snow may be used, and the tracks covered therewith in advance of the snow-plow car. For example, bits of whitened cork or small cotton balls as represented at 136 in Figure 6, or the like.

25 The child operating the train may open the doors 119 and lower the scrapers 123, using either or both features as he pleases.

30 In Figure 17 is shown a modified form of snow-plow car 20x, wherein the shaft 32 and rotary plow 35 are omitted, a plain stationary plow 35x being substituted.

35 In Figures 18, 19, 20 there is shown a modified form of locomotive 40x, and operating features. In this modification the bell 45x is operated by a bellows 137 having one side anchored to a bracket 138 extended from the bottom of the locomotive. A pedal 139 depends from the other and movable side of the bellows and contacts a double cam 140 on the frontal axle 55x. The bell is swingingly suspended at the upper extended end 141 of the movable side of the bellows. A hollow, puff-producing baffle element 105x is mounted in one side of the bellows for simulating an engine. An air intake valve 104x is mounted in the other side.

40 A similar bellows 142 is horizontally mounted under the dummy whistle 46x, being suspended from a bracket 143 attached to the top of the locomotive and to the upper side of the bellows. An arm 144 is hingedly depended from the lower side of the bellows and having an eye 145 at its lower end. A spring 146 normally closes the bellows. An air intake valve 104y is mounted in one side, and a musical reed unit or siren 147 is mounted in the other side, adapted to be operated by air forced therethrough from the bellows.

45 A worm 148 is mounted on the adjacent axle 55y and placed in mesh with a worm wheel 149 on a stub shaft 150 journaled in a bracket 151 anchored to the frame of the locomotive. A finger 152 is loosely journaled at one end upon the end

of the shaft 150 remote from the worm-wheel 149 and has its free end 153 turned outwardly and placed into free engagement with the eye 145 of the bellows operating arm 144.

A trip-latch or trigger 154 is anchored at one end 155 to the stub shaft 150 while the other end 156 extends out across the finger 152, at one side thereof, in spaced relation to the shaft 150. Thus as the locomotive travels, the shaft 150 revolves and the trigger end 156 forces the finger 152 around by contact therewith at one side of the finger. On the descending movement of this finger it will therefore open the bellows against the pull of the spring 146, but when the finger has reached its lowest limit of travel and starts to move upward at the opposite side of its orbit, it is freed from the restraint of the trigger and the spring 146 jerks it shut, thus forcing air through and operating the siren.

In this form of the locomotive the motor 12x is mounted transversely in the locomotive, and its shaft 19x has a pinion gear 85x in mesh with the drive gear 86x of the shaft 87. Otherwise the drive gears are identical with the first form.

In constructing the train any of the desirable structural features that might be wanted, may be selected and assembled in such train.

While I have here shown and described certain embodiments and structural features of the invention, these may be changed or modified within the scope of the claims.

I claim:

1. In combination, a toy locomotive and tender and snow-plow car for positioning in front of the locomotive, a shaft longitudinally journaled through the locomotive and tender and projected at the front of the locomotive, said projected end

carrying a squared, tubular coupling axially aligned with the main shaft, a shaft similarly journaled through the snow-plow car, in alignment with the shaft of the locomotive shaft, a rotary plow mounted on the forward extended end of the snow-plow car shaft, and a spear-head coupling, squared at its base, carried by the rear end of said shaft the same being dimensioned to slide nicely into the tubular coupling of the locomotive shaft, and means for rotating the said shafts.

5 2. In a device of the kind described, a wheel-borne locomotive and tender, and a wheel-borne snow-plow car located forwardly of the locomotive, a shaft journaled longitudinally through the locomotive and tender, a separate shaft journaled longitudinally through the snow plow car, means 15 for connecting the shafts, means in the tender for rotating the shafts for operating attached accessories of the assembly.

10 3. In a device of the kind described for operation upon a toy track having imitation snow loosely laid thereon, a toy wheel-borne snow-plow car and wheel borne locomotive upon the track in conventional order, the locomotive and snow-plow car being equipped with conventional accessories, shafts journaled longitudinally through the locomotive and snow-plow car, means for rotating the said shafts, and means 20 connecting the shafts with the locomotive accessories and snow-plow car accessories for operating the latter by the rotation of the former.

25 4. In a device according to claim 3, means connecting the shafts with the locomotive wheels for propelling the locomotive by the rotation of the shafts.

PATRICK E. E. CODERRE.
